UNITED STATES PATENT OFFICE.

FRANCIS MARTIN, OF SAN FRANCISCO, CALIFORNIA.

DAVENPORT.

1,223,285.

Specification of Letters Patent. Patented Apr. 17, 1917.

Application filed April 29, 1914. Serial No. 835,294.

To all whom it may concern:

Be it known that I, FRANCIS MARTIN, a citizen of the United States, residing at 1452 Filbert street, in the city and county of San Francisco, State of California, have invented a new and useful Improvement in Davenports, of which the following is a specification.

This invention relates to improvements in 10 "davenports", and more particularly to convertible sofa beds.

Among the objects of this invention are to provide a convertible sofa, having a mattress foldable within said sofa; and

15 To provide sufficient room between the folds of said mattress to contain the bed clothing without undue compression; whereby a fully made up bed may be folded within the sofa.

20 The preferred form of putting this invention into practice is illustrated in the drawings accompanying and forming part of the present specification, to which like reference characters are applied to the various parts. The novelty of the invention is included in the claims following the description, but I do not wish to be understood as limiting myself, to the disclosures made in said drawing and description, as 25 many modifications are available within the spirit of this invention as defined in said claims.

Figure 1— is a side elevation in longitudinal cross section of a convertible bed constructed in accordance with this invention, shown in the unfolded position.

Fig. 2— is a similar view of the same showing the bed in the folded position.

Fig. 3— is a fragmentary detail in cross 40 section of the link hinge by which the swinging section of the sofa is supported.

Fig. 4— is a fragmentary detail in front elevation of the supporting leg for the outer edge of the swinging section of the sofa.

45 In detail the construction illustrated in the drawings includes the sofa frame, having the front posts 1, the rear posts 2 and the sides 3. The back of the sofa between the sides 3 may be upholstered as indicated

50 in the dotted lines 4. The rectangular mattress frame is composed of the side sections 5, 6 and 7, joined by the links 8 and 9 on opposite sides of the frame forming hinges by which the mattress is folded upon itself 55 as in Fig. 2. The mattress frame is preferably composed of angle iron including the

ends 10 and 11, forming a rectangular frame within which any desirable spring mattress surface may be suspended; that form preferred by me consists of a wire mesh center, 60 suspended by spiral springs at intervals engaging said mesh and the frame.

The head section is supported by the swing arm 12 pivoted at 13, on the plate 14, fixed to the side board 15 joining the posts 65 1 and 2. The other end of the arm 12 is pivoted at 16, near the end of the head section. The side bars 5 are hinged on the pins 17 in the links 8. The links 8 are supported by the brackets 18, pivoted thereto 70 on the pins 19 and fixed to the hinged seat section 20 of the sofa. The side bars 6 are centrally supported by the swing arms 21 pivoted thereto at 22 and at 23 to the seat section 20, the opposite ends of the bar 6 75 hinging on the pins 24 and 25 in the links 8 and 9 respectively. The foot section is supported by the side rails 7, pivoted on the pins 26 in the links 9, the other ends being supported by the pins 27 upon which the 80 legs 28 are hinged. These legs are held in the proper upright position by the latches 29 pivoted at 30 on the legs and having slots 31 engaging the pins 32, fixed in the sides 7; when the legs swing to the upright position, 85 the latches automatically drop into position so that the lateral notches 33 forming part of the slots, engage the pins 32 as shown in Fig. 1. The hinged seat section 20 is supported by the legs 34, pivoted at 35; when 90 this section is swung open these legs drop into position by gravity. This section 20 is hinged to the main sofa frame by the links 35, pivoted at 36 near the opposite corners of this section. The upper ends of these 95 links are pivoted at 37 on the bracket 38, extending upward from the plate 14; these links thus supporting the inner side of the section 20, and permitting its proper evolution in the closing operation. The various 100 mechanisms shown in the drawings are the same on each side of the bed.

The operation of folding up the bed is as follows:—

Lifting the end rail 11, causes the side 105 rails 7 to hinge on the centers 25 and 26, permitting the foot section to fold inward and overlie the intermediate section, represented by the side rail 6, the length of the link 9 accommodating the thickness of bed 110 clothing, that is properly secured to the mattress by straps or other retaining means; in

this position the latches 29 are released from the pins 32 which permits the legs 28 to collapse and lie within and parallel with the side rails 7. The notches 39 on the fixed 5 latches 40, that are rigidly fixed at the proper angle to the legs 28, engage the studs 41 extending outward from the sides 6. The resiliency in the bend 42 permits the latches 40 to spring sufficiently, to engage the studs 10 41, with the proper tension. In opening the bed, these latches 40 are released by sufficient pull on the cross rod 43, having its opposite ends riveted through the legs 28.

With the foot section thus folded back 15 over the intermediate section, the seat section 20 is swung upward and inward on the supporting links 35. The connecting arms 44 are pivoted at 45 on the brackets 18 and at 46 on the bell crank levers 47, fulcrumed 20 at 48 on the plates 14. The opposite ends of the bell crank levers are pivoted at 49 to the connecting arms 50, in turn pivoted at 51 to the side rails 5 of the head section. The inward swing of the seat section 20, 25 causes the connecting arms 44 operating through the bell cranks 47 and connecting arms 50, to pull downward the side rail 5 of the head section; simultaneously the tensions of the spiral springs 52 attached to 30 the head rail 10 and the brackets 53, fixed to the back board 54 of the sofa frame, pull the head section inward and downward until the seat section begins to descend from the vertical, the side rails 6 and links 8, hinging 35 on their centers 17 and 24. In the folded position the link 21, centers the section 6, inside the seat section 20.

The weight of the descending seat section with its associated parts, depresses the head 40 section to the position shown in Fig. 2. The tensions of the springs 52 assist in carrying the various pivotal members past their dead centers, until the weight of the folded parts, completes the various closing actions by 45 gravity; thus making very easy the action of closing or folding up the bed. Having passed the dead center, these springs react to ease the descending weight of the folded mattress; and similarly aid in the opening 50 operation, that is obviously, simply a reversal of the closing operation.

The legs 34 drop by gravity from the

latches 55, into which they drop by gravity during the closing operation; the last act in the opening operation is to grasp the rod 43 55 exerting sufficient pull to release the latches 40, and swing the legs 28 and the latches 29 into their respective operative positions.

The mattress frame is provided with spreaders X extending across the frame and 60 attached to the links 8 and 9. The spreader is omitted from the drawing between the links 8 to avoid confusion. The plates 14 with the various parts attached thereto and pivoted thereon are introduced as a convenience in assembling the mattress in the sofa; in this manner insuring the proper relation of the part.

Having thus described this invention, what I claim and desire to secure by Letters 70 Patent is:

1. A folding bed comprising a main frame, a swinging seat hinged near the front edge of said main frame, a jointed mattress having head, intermediate, and foot 75 sections, swing arms pivoted to said head section and said frame, swing arms pivoted to said intermediate section and swinging seat, supporting legs on said foot section, a bracket mounted on said seat between the 80 head and the intermediate sections, a lever pivoted intermediate its ends on the main frame, a connecting link pivoted to said bracket and to one end of said lever, and a link pivoted to the head section and to the 85 other end of the lever.

2. A folding bed comprising a main frame, a swinging seat hinged near the front edge of said main frame; a jointed mattress having head, intermediate, and foot 90 sections; swing arms pivoted to said head section and to the main frame; a lever pivoted on the main frame; a link pivoted on said head section, and to one end of said lever; a link pivoted to the opposite end of 95 said lever and to said swinging seat; and supporting legs on said foot section.

In testimony whereof, I have hereunto set my hand this 16th day of April 1914.

FRANCIS MARTIN.
